UNITED STATES PATENT OFFICE

91,410

DESIGN FOR AN AUTOMOBILE BODY

Amos E. Northup, Pleasant Ridge, Mich., assignor
to The Murray Corporation of America, Detroit,
Mich., a corporation of Delaware

Continuation of application Serial No. 43,956,
June 2, 1932. This application March 9, 1933.
Serial No. 47,419

Term of patent 7 years

To all whom it may concern:

Be it known that I, AMOS E. NORTHUP, a citizen of the United States, residing at Pleasant Ridge, in the county of Oakland, State of Michigan, have invented a new, original, and ornamental Design for Automobile Body, of which the following is a specification, reference being had to the accompanying drawing, forming a part thereof, wherein:

In the drawing Figure 1 is a perspective view of an automobile body embracing the principles of my new design and of which the rear end of the body is the dominant part.

Figure 2 is a horizontal sectional view of the body across the rear end thereof and particularly illustrating a plan view of the dominant part of the design.

The dominant feature of my design comprises the appearance of the rear end of the body as shown in the full lines in Figures 1 and 2. The

parts shown in the dotted lines are illustrative of a conventional standard type of automobile body, except the front end including the forward corners and parts surrounding the windshield (Fig. 1) which is the subject of my copending application, Serial No. D-42,895, filed February 17, 1932 Patent #89,448—patented March 14, 1933. The said dominant feature may be employed and embodied without substantial change, in the following conventional types of automobile bodies; four door sedans, coaches or two door sedans, and victorias.

This application is a continuation of my copending application, Serial No. 43,956 filed June 2, 1932 and covering the same subject matter.

I claim:

The ornamental design for an automobile body substantially as described and shown.

AMOS E. NORTHUP.
